(57) **CLAIM**

The ornamental design for a multi-function tool, as shown and described.

DESCRIPTION

FIG. 1 is a perspective view of the multi-function tool showing our new design;

FIG. 2 is a left elevation view thereof;

FIG. 3 is a right elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines shown in the drawings illustrate portions of the multi-function tool that form no part of the claimed design.
